EDWARD A. DEWALD, OF MASSILLON, OHIO, ASSIGNOR TO THE GRISCOM-RUSSELL COMPANY, OF NEW YORK, N. Y., A CORPORATION OF DELAWARE.

RETURN BEND FOR FIN TUBES.

Application filed December 28, 1927. Serial No. 242,045.

This invention relates to heat-radiating devices of the type employed for cooling heated liquids, such, for example, as the liquefied refrigerating agent of refrigerating apparatus.

The object of the invention is to provide an apparatus of this kind employing thin tubing of small diameter provided with radiating fins which interfere with the tubes being 10 bent or coiled, but which may be built at a cost little greater than radiators formed of continuous tubing. To this end my improved heat-radiating apparatus is composed of a series of straight tubes extending between 15 suitable supports with the ends of the adjacent tubes connected together by means of return bends connected to the ends of the tubes by means of an improved joint which is readily completed with hand tools after 20 the tubes are inserted in the supports.

The tubes forming the tube bank may be connected in any desired series-parallel arrangement to provide a flow path having the necessary length and cross section for 25 the cooling effect which it is desired to obtain.

In the accompanying drawings I have shown a complete radiating apparatus composed of three parallel units, each unit having six tubes connected in series.

30 In said drawings

Figure 1 is a side elevation of the assembled radiator;

Fig. 2 is an end view looking from the right of Fig. 1;

35 Fig. 3 is an enlarged side view of one of the return bends, one side being shown in section; and

Figs. 4 and 5 are sectional views of modified forms of joints which may be employed 40 in lieu of the joint shown in Fig. 3.

Referring to the drawings, the radiator is composed of two supporting plates 1 which are fixed in place in proper spaced relation on any suitable base, not shown. Extending 45 from one plate to the other are a series of radiating tubes 2, of which eighteen are shown in the drawing, the tubes being arranged in three vertical rows of six each.

The tubing which I prefer to employ is a 50 thin copper tubing of small diameter having a closely-wound spiral heat-radiating fin 4 attached to its outer surface. The tubes are

preferably formed in lengths slightly greater than the distance between the two supports 1, 1, so that the tube projects beyond the outer 55 faces of the supports at each end. The tubes may be originally formed of the desired length, in which case the spiral fin is not extended to the extreme ends of the tubes but extends merely from inner face to inner 60 face of the two supports.

The tubes may, however, be cut from continuous lengths of the thin tubing and the fin removed at each end to provide the necessary projecting ends for receiving the return 65 bends 3. As shown in Fig. 3, the supports 1 consist of metal plates and the ends of the tubes are supported in holes in the plates, which holes are of a diameter on the inner 70 face of the plates to accurately fit the tubes while on the outer face of the plates the holes are of larger diameter, thereby providing 75 annular wedge-shaped recesses 6 between the walls of the tubes and the walls of the holes in which they are supported.

The ends of the tubes are provided with 80 annular grooves 7 immediately beyond the outer face of the supporting plates 1, the grooves preferably being rolled into the tubes prior to the assembly of the tubes in 85 the supports 1. This operation may be readily performed while the tubes are in the fin-winding machine by means of grooving rollers whereby the tube sections of proper length with their ends ready to receive the return bends, may be produced without additional cost.

Each return bend 3 consists of a U-shaped tubular member of a bore corresponding with the bore of the tubes and with its two legs 90 spaced apart a distance corresponding to the spacing of the tubes in the supports. Each end of the return bend is enlarged to provide an inside diameter equal to the outside diameter of the tubes, the enlarged portion being 95 of a depth to permit the bend to telescope over the ends of the tubes to a sufficient extent for the edge of the bend to be crimped into the groove 7 as indicated at 9, and thereby form an interlocking joint between the 100 tubes and the return bend. To facilitate the crimping of the bends into the tubes the metal of the bends is notched or cut away on four sides as indicated at 8, the notches allowing

the metal on each side of the notches to be drawn together as the bead is formed, for which purpose an ordinary hand-operated crimping tool is quite sufficient.

- 5 In Fig. 3 the joint at the upper side of the figure is shown in elevation as it appears after the crimping operation. In order to render the joints air-and-water-tight and also to unite the tubes rigidly in the support and 10 reinforce the joints against separation under rough usage, each joint is surrounded with a ring 10 of solder which extends into the V-shaped annular opening 6 between the tube and the supporting plate, and also extends 15 beyond the ends of the notches 8 in the ends of the return bends. After applying the solder it is preferably "wiped" to form a triangular fillet adhering along its radial surface to the face of the plate and 20 completely closing the joint against leakage.

A radiator of any desired capacity may readily be made according to the present invention. The tube lengths are all uniform and may all be beaded before assembly. The 25 return bends likewise are all uniform and may have their ends extended and edges slotted in the manner shown during the process of manufacture. The supporting plates are punched to fit the tubes and after 30 the tubes are assembled in the plates they may be fastened together in any suitable manner, as, for instance, by bolts at the top and bottom which hold the parts assembled as a unit while the return bends are being attached. After the return bends are attached 35 in the manner shown the two manifolds 5 may be applied to the projecting ends of the upper and lower banks of tubes by means of similar joints or otherwise, as may be desired.

In Fig. 4 I have illustrated a modified form of joint wherein a bead 12 is provided on the projecting ends of the tubes instead of the groove 7. In this form of joint the 45 ends of the bends are slotted to a greater depth than in the previously described case and are slipped over the ends of the tubes and crimped over the beads as shown at 13. The joint is then soldered with a fillet of solder 50 covering the joint and anchoring the tubes to the supporting pipe. The making of this type of joint will be greatly facilitated by enlarging the bends during the process of manufacture to provide a shoulder at the 55 point where the bead 13 comes, so that all that is necessary after the radiator is assembled is to bend down the ends of the projecting tongues between the slots with the hand crimping tool. For this type of joint the 60 beads at one end of the tubes are formed after the tubes are assembled in the plates.

In Fig. 5 I have shown a further modified form of joint wherein the ends of the tubes are slotted and expanded to form a bead 65 or shoulder 14 which fits into an annular

groove 15 formed in the inner wall of the return bend. This joint may be employed with advantage where the metal of the tubes is sufficiently elastic for the previously slotted and flared tube end to be contracted and 70 thrust into the end of the return bend to expand of its own resiliency into interlocking engagement with the groove of the bend. A small fillet of solder is applied to this joint also. This joint may also be used where the 75 metal of the bend is soft enough to be rolled down into engagement with the wall of the tube by a hand-manipulated tool without being slotted.

It will be obvious that the joint between 80 the tube sections and the return bends may be otherwise modified without departing from the spirit of the invention, the essential features of which are the mechanical interlocking of the tubes and bends in a manner 85 readily accomplished with a hand tool and then reinforcing the joint with a soldered fillet or other sealing means applied in the manner defined in the following claims.

I claim:

1. In a heat-radiating apparatus the combination of a series of straight tube sections having radiating fins, means for supporting said tube sections in substantially parallel arrangement, return bends connecting the 95 adjacent ends of said tube sections to form a continuous flow path, interlocking parts on said tube sections and said bends for joining them together, and a fillet of solder enclosing said interlocking parts and adhering 100 to the face of the adjacent support.

2. In an apparatus of the class described, the combination of a support, a tube section supported therein, a second tubular member in telescopic engagement therewith and 105 means connecting said section, said member and said support, said means comprising interlocking parts on said tube section and said member respectively, and a soldered connection between said tube section and said support, said soldered connection overlying and sealing the joint between the tube section and 110 said tubular member.

3. In an apparatus of the class described, the combination of a supporting bar having an opening, a tubular member supported therein, a recess in said bar surrounding said member, a second tubular member in telescopic engagement with said first member and means connecting said members and said support comprising interlocking parts on said members, and a fillet of solder surrounding 115 said interlocking parts and extending into the recess in said support.

4. In an apparatus of the class described, the combination of two telescoping tubular members, interlocking parts on said members comprising a circumferential groove in one of said members, longitudinally extending 120 tongues on the other of said members, 125

130

said tongues being bent radially to project into said groove, and means for permanently sealing said parts together.

5. In an apparatus of the class described the combination of two telescoping tubular members, interlocking parts on said members comprising a circumferential groove in one of said members, longitudinally extend-

ing tongues on the other of said members, said tongues being bent radially to project into said groove, and means for permanently sealing said parts together, said means comprising a ring of solder enclosing said interlocking parts and adhering to both said parts.

In testimony whereof I affix my signature.
EDWARD A. DEWALD.
